TRAFFIC SIGNAL

John Sheedy, Seattle, Wash.

Application September 25, 1929
Serial No. 395,153

4 Claims. (Cl. 177—329)

My invention relates to the art of signaling and particularly to that branch of the art having to do with the directing of traffic at street or road intersections.

5 Primarily the invention has for its object to provide a traffic signal of the semaphore "stop-go" light type and it especially seeks to provide such a signal in which the "stop" semaphores are constantly moving into and out of position and 10 the "stop" and "go" lights are operated at proper time intervals in association with the movements of the semaphore.

Another object is to provide a signal in which the "go" signal does not change position but remains at one place and is illuminated at proper intervals to be visible or not accordingly as the light is energized or de-energized, and according to the position of the "stop" semaphore.

Again the invention has for an object the provision of means whereby the time interval between signal light changes may be easily varied or adjusted to suit conditions met with in practice.

Again it is an object to provide a signal of the character stated which may be suspended over street intersections or to be mounted on posts or poles as desired.

Other objects will in part be obvious and in part be pointed out hereinafter.

To the attainment of the aforesaid objects and 30 ends the invention resides in those novel combinations, arrangements and constructions of parts which will be first described, then be specifically pointed out in the appended claims and illustrated in the accompanying drawings, in 35 which:

Figure 1 is a perspective view of a preferred embodiment of the invention.

Figure 2 is a vertical longitudinal section, the "go" signal being in operation.

40 Figure 3 is a similar view the "stop" semaphores being projected and the "stop" signal lights lit to indicate the "stop" signal.

Figure 4 is a horizontal section taken in a plane just below the lower edge of the top of the casing 45 1.

Figure 5 is a circuit wiring diagram of the electrical connections.

Figure 6 is a detail vertical section on the line 50 6—6 of Figure 4.

In the drawings, in which like numerals of reference indicate like parts in all the figures relating to a single embodiment of the invention, 1 represents a rectangular casing having "stop" 55 windows 2 in its front and back faces adjacent the ends and "go" windows 3 intermediate its ends.

4 designates a pair of "stop" semaphores carried on bars 5 which have racks 6 to mesh with a 60 drive pinion 7 on the shaft 8 which is driven

through a suitable gear train 10 from a reversible electric motor 9.

The motor 9 is controlled by a motor reversing switch 11 hereinafter again referred to.

12 is the "go" light which is contained within 65 a tubular housing so as to project its rays through the "go" windows 3 only, while 13 and 14 designate the "stop" lights carried by the "stop" semaphores 4—4.

The "go" light housing 15 also serves as a 70 support for a loose ring 16 which has gear teeth 17 to mesh with an operating rack 18 on one of the bars 5 and which also has a switch actuating finger 19 to cooperate with the operating fingers 23—24 of the "stop" and "go" controlling switch 20. When the parts are in the position shown in Figures 6, and 19 turns clockwise it will engage 24 and move it down to the dotted line position out of the path of movement of member 19, member 23 following after it into 80 the path of movement of member 19 on reverse movement of member 19, it engages member 23 and moves it out of the path of movement while putting member 24 into the path of movement.

The motor reversing switch is provided with 85 operating fingers 21 to be operated by a finger 26 on one of the rack bars 5 as the "stop" signals 4 reach the limit of their in and out movement.

A top red light 27 may be mounted on the casing 1 and connected to be illuminated when the "stop" signal lights are turned on.

In the wiring diagram relating to the first embodiment of the invention, 25 designates the main line wires which supply current to the motor circuits in which is contained the motor 9 and the motor reversing switch 11 and which also supply current to the "go" and "stop" lights 12—13—14 and in which light circuits the control switch 20 is contained, as will be clear by reference to Figure 5.

So far as described, my invention operates as follows: Assume that the switch 20 is set so as to energize the "go" signal light 12 and assume that the "stop" semaphores 4 are in the retracted position, the motor turning to move the semaphores outwardly to their signaling position; as soon as the semaphores have been moved toward their signaling position a distance sufficient for the ring gear 16 to bring its finger into engagement with the finger 23 of the light switch 20 it will snap that switch over or throw it over to the opposite position where it will put the "stop" lights in circuit and extinguish the "go" light. The "stop" lights then continue burning until the semaphores have moved outwardly to their extreme projected position at which time a "stop" finger 26 will engage the motor reversing switch figure 21 of the motor reversing switch 11 and throw it to the position indicated

in dotted lines in Fig. 3, thus causing the motor to reverse and begin moving the semaphores 4 inwardly. The red signal lights remain burning, however, until the finger 19 on its return movement reverses the position of the switch 20 by engaging the finger 24 to restore the "go" light and extinguish the "stop" light. The semaphore continues travelling inwardly until a finger 26 engages the motor reversing switch finger 21 and again reverses the action of the motor, thus completing the cycle of operations.

It will be observed that in practice the loose ring 16 is of greater diameter and has a greater number of gear teeth than the rack which engages it so that it will not make a complete revolution to each reciprocation of the rack. Thus, by changing the mesh of the loose ring 16 with the rack that engages it the position of the finger 19 may be changed to advance or retard the time of the operation of the switch 20. For example, if the finger 19 is set in a certain position the timing is such that the switch 20 will be operated to turn off the "go" and turn on the "stop" lights as soon as the semaphore disks begin to intersect the "stop" windows and allow the "stop" light to remain on until the semaphores have reached their complete projected position and have returned to the position where the switch 20 had been operated before the finger 19 will reset the switch 20 to extinguish the "stop" lights and turn on the "go" lights position of the ring 16 with respect to its operating rack the finger 19 may be caused to operate the switch 20 when the "stop" semaphore has reached say the half-way projected position, thus changing the relative interval between the "stop" and "go" periods, or instead of changing the position of the ring 9, rings of different diameters may be employed for the purpose of changing the timing, as will be evident to those skilled in the art.

While I have disclosed the invention for giving signals both ways along one direction, it is obvious that it may be duplicated to give signals both ways along two directions, as at street crossings but as that will be a mere duplication of parts illustration thereof is thought to be unnecessary.

If desired, the box or casing 1 may be provided with street indicating signs designated generally by the reference character 54, thereby assisting in the direction of traffic.

From the foregoing description, taken in connection with the accompanying drawings, it is thought that the complete construction, operation and advantages of my invention will be readily understood by those skilled in the art.

What I claim is:

1. In an electrically actuated traffic signal, a casing having a "go" signal window and a separate "stop" signal window, a signal light mounted within the casing in a position to cast its rays through the "go" signal window when the light is energized, a "stop" signal semaphore located within the casing and having a translucent portion and a "stop" light carried thereby to illuminate said translucent portion when said "stop" light is energized, a motor, and power transmitting mechanism between said motor and said semaphore for moving said semaphore to place its translucent portion into and out of register with said "stop" signal window alternately, means for effecting reversal of the motor action at definite time intervals to bring said semaphore with its translucent portion into and out of register

alternately with said "stop" signal window and means for periodically energizing and extinguishing said "stop" and "go" lights alternately accordingly as said "stop" semaphore's translucent portion and its light are visible through said "stop" signal window or not. 80

2. In an electrically actuated traffic signal, a casing having a "go" signal window and a separate "stop" signal window, a signal light mounted within the casing in a position to cast its rays through the "go" signal window when the light is energized, a "stop" signal semaphore located within the casing and having a translucent portion and a "stop" light carried thereby to illuminate said translucent portion when said "stop" light is energized, a motor, and power transmitting mechanism between said motor and said semaphore for moving said semaphore to place its translucent portion into and out of register with said "stop" signal window alternately, means for effecting reversal of the motor action at definite time intervals to bring said semaphore with its translucent portion into and out of register alternately with said "stop" signal window, means for periodically energizing and extinguishing said "stop" and "go" lights alternately accordingly as said "stop" semaphore's translucent portion and its light are visible through said "stop" signal window or not, and a translucent globe on top of said casing and a light within the globe, means for energizing and extinguishing said light in accordance with said "stop" light. 90

3. A totally enclosed traffic signal comprising a casing having a "go" signal window and a separate "stop" signal window, a reciprocating semaphore enclosed within said casing, means for moving said semaphore into juxtaposition with said "stop" signal window so as to be visible therethrough at the latter part of its reciprocating movement and be in register therewith substantially at the end of its movement, a "stop" light on the semaphore within the casing to illuminate the semaphore during a part of the time when it is in the aforementioned positions with respect to the "stop" window so that the semaphore will give a signal, a cooperating light within the casing for the "go" signal window to give the "go" signal alternately with the "stop" signal, means within the casing and operated by one complete reciprocation back and forth of the semaphore to accomplish the alternate display of said lights, the time of one cycle being coincident with one complete reciprocation back and forth of the semaphore. 100

4. In a traffic signal, a casing having a "go" signal window and a "stop" signal window, a fixed "go" light within the casing in alignment with the "go" signal window, a rack bar reciprocably mounted within the casing, a "stop" signal lantern carried by said bar and visible through said "stop" signal window when said lantern is in alignment therewith, a positively actuated motor geared to said rack bar and located within the casing and a motor reversing switch mechanism cooperating with said motor for reciprocating the rack bar to bring its lantern alternately into and out of register with said "stop" signal window, a "stop" light in said lantern, light circuits for said "stop" and "go" lights and a switch therefor in circuit with said lights for alternately energizing and extinguishing said lights, and means to operate said switch by the reciprocation of said rack bar. 110

JOHN SHEEDY. 150
